UNITED STATES PATENT OFFICE.

JOHN C. BLEVNEY, OF NEWARK, NEW JERSEY.

GRINDING AND POLISHING MACHINE.

1,134,508.

Specification of Letters Patent.

Patented Apr. 6, 1915.

Application filed March 26, 1914. Serial No. 827,284.

To all whom it may concern:

Be it known that I, JOHN C. BLEVNEY, a citizen of the United States, residing at Newark, in the county of Essex and State 5 of New Jersey, have invented certain new and useful Improvements in Grinding and Polishing Machines; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification. 15

This invention has reference, generally, to improvements in grinding and polishing machinery; and the said invention relates, more particularly, to a novel construction of 20 machine for grinding and polishing the rough uneven surfaces of metal castings, and the like.

The invention has for its principal object to provide an efficient construction of apparatus adapted to automatically grind and polish the rough uneven surfaces of metal castings, and the like, to provide the same with an apparently smooth evenly finished surface, without, however, unduly grinding 30 off the high spots or points forming the surface inequalities of the said castings, so that said castings are weakened or rendered too thin by the loss of metal. To accomplish this end I provide a novel means for pressing 35 the abrading elements of the machine in contact with all portions of the area of the unequal surface of the castings with substantial uniformity.

Another object of the present invention is 40 to provide a novel means for feeding the castings in contact with the abrading elements of the machine, so that the casting is moved laterally across the faces of the abrading elements, and at the same time I 45 provide for a corresponding relative movement of the means for pressing the abrading elements to the surfaces of the casting.

A still further object of the invention is 50 to provide, in connection with the novel work feeding means, devices whereby the movement of the work is accelerated, in adjustable ratios, with relation to the movement of the means for pressing the abrading elements to the work, the purpose and benefits 55 of such arrangements being more fully

defined and described in the following specification.

Other objects of the present invention, not at this time more particularly enumerated, will be clearly understood from the following detailed description of this invention. 60

With the various objects of the present invention in view, the same consists, primarily, in the novel grinding and polishing machine hereinafter set forth; and, the invention consists, furthermore, in the novel arrangements and combinations of the several devices and parts, as well as in the details of the construction of the same, all of which will be more fully described in the 70 following specification, and then finally embodied in the claims which are appended to and which form an essential part of the said specifications.

The invention is clearly illustrated in the 75 accompanying drawings, in which:-

Figure 1 is a front elevation of the grinding and polishing machine made according to and embodying one form of my present invention. Fig. 2 is a vertical longitudinal 80 section of the same, taken on line 2-2 in said Fig. 1. Fig. 3 is a detail vertical section similar to said Fig. 2, but confined more especially to the work feeding mechanism and associated parts, said view being drawn 85 on an enlarged scale, and the limit of the operative movement of the various parts therein illustrated being indicated by dotted line representation. Fig. 4 is a detail transverse section taken on line 4-4 in said Fig. 90 3, looking in the direction of the arrow α ; and Fig. 5 is a detail horizontal section taken on line 5-5 in said Fig. 4, looking downward; the limit of the operative movement of the various parts illustrated in both 95 Figs. 4 and 5 being indicated by dotted representation in said respective views. Fig. 6 is a detail longitudinal vertical section of one of the devices comprising the means for pressing the abrading elements of the machine to the work. Fig. 7 is a view similar 100 to that shown in Fig. 5, but illustrating a slightly modified construction and arrangement of the means for pressing the abrading elements of the machine to the work. 105

Similar characters of reference are employed in all of the hereinabove described views, to indicate corresponding parts.

Referring now to said drawings the reference character 1 indicates the base of the 110

novel grinding and polishing machine forming one embodiment of my present invention, the same being provided upon its sides with transverse guide-channels 2. Mounted 5 upon said base 1 are a pair of laterally movable standards 3, the lower ends of which are provided with retaining-plates 4, which ride in said guide-channels 2, and which, while permitting the lateral movement of 10 said standards 3 upon the base 1, prevent any displacement of the same from said base 1.

Journaled in the lower portion of each standard 3 are shafts 5. One of said shafts 5 is provided with a driving pulley 6. Secured 15 upon the forwardly projecting end of each shaft 5 is a pulley-wheel 7. The respective pulley-wheels 7 must preferably be drawn in opposite directions, and while each could be driven separately to accomplish 20 this end, I prefer to use the following driving means. The shaft 5 which is driven by the driving pulley 6 is provided with a pulley 8 over which runs the belt 9. Said belt is carried over a pulley 10 mounted rotatably within said base 1, thence passing over 25 a pulley 11 which is journaled in movable bearings 12 secured within said base 1, thence over a pulley 13 connected with the other of said shafts 5, thence being carried 30 over a pulley 14 mounted rotatably within said base 1, thence over a pulley 15 which is journaled in movable bearings 16 secured within said base 1, and thence returning over the said pulley 8. The said belt 9 is 35 twisted in those portions of its stretches which extend between the pulleys 10 and 11 and the pulleys 14 and 15, so that said stretches of the belt will pass each other without interference. By such an arrangement 40 it will be apparent that the driven shaft 5 will transmit its rotation to the other shaft 5, the rotation of the latter being reversed, so that the respective pulley-wheels 7 will be driven in opposite directions.

45 The reference character 17 indicates pulley wheels which are rotatably journaled in movable bearing members 18 which are respectively mounted in connection with the respective standards 3.

50 The reference character 19 indicates pulley-wheels which are rotatably journaled in movable bearing members 20 which are respectively mounted in connection with the respective standards 3.

55 The reference character 21 indicates backing belts having transversely grooved outer faces, the same respectively running over the pulley wheels 7 and 17 of each standard 3. The reference character 22 indicates abrading 60 belts, the outer surfaces of which are provided with a covering of some suitable abrading material such as carborundum, emery or the like. The said abrading belts 22 extend over the pulley wheels 19 of each standard so as to pass around and over the

backing belts 21. Since the pulley wheels 7 are driven in opposite directions the said backing belts 21 are driven respectively in opposite directions, and in turn drive said abrading belts 22, which they back, also in 70 opposite directions. The respective pulley wheels 7 and 17 of each standard 3 are so arranged and aligned relatively to one another that the inner stretches of said backing belts, and that portion of said abrading 75 belts riding upon said inner stretches, are caused to run parallel to each other, the abrading surfaces of the respective abrading belts facing each other so that a casting or other work to be ground may be inserted 80 therebetween so that the opposite faces of the same are simultaneously operated upon by said abrading belts. Since the sizes and thicknesses of the castings desired to be ground may be various it is of course necessary to mount the respective abrading belts so that the distance between their parallel 85 surfaces may be varied to properly accommodate the size of casting to be operated upon, and to this end said standards 3 are 90 made movable upon said base 1, as above indicated, so that the same may be set closer or farther apart to thereby carry said abrading belts nearer together or farther apart as the case may be. 95

The reference character 23 indicates outwardly projecting bracket arms which are secured to the outer side surfaces of the respective standards 3 so as to extend forwardly therefrom. Each bracket arm is 100 provided with a pair of bearing blocks 24. Journaled in and extending between oppositely facing bearing blocks 24 are a pair of supporting shafts 25 and 25' from which depend pairs of parallel lever-members 26 and 26'. Connected pivotally with the lower ends of said lever-members 26 and 26' by means of bolts 27 is a carrier table 28. By reason of its support by the parallel lever-members said carrier table 28 is always 110 maintained in a level horizontal position even during the forward swinging movement of the same as controlled by said lever-members.

Various forms of work holding devices 115 may be secured upon said carrier table 28 each being suited to the shape of the work to be operated upon. In the drawings, as an example of one of such work holding devices, I have illustrated a work holding 120 means adapted to carry a casting such as a wrench-frame for Stillson wrenches, the same comprising an angle-plate or bracket 29, the same being secured upon said carrier table by means of anchor-bolts 30, the heads of 125 which are secured in one of a plurality of inverted T shaped grooves 31, which extend transversely across said carrier table. The face of said angle-plate or bracket 29 is provided with a pair of yoke-pieces 32 through 130

the openings of which extends a movable carrier-arm 33. Said carrier-arm is slidable in said yoke-pieces toward the abrading belts 22, and the same is provided with a 5 stop-pin 34, which engaging one of said yoke-pieces limits its inwardly pushed movement. When pushed inward said carrier-arm is locked against any backward or outward movement by means of a notch or cut- 10 away portion 35, which is provided in its upper marginal edge, and which receives the upper portion of one of said yoke-pieces. Said carrier-arm being so constructed that its inner end overbalances its outer end, its 15 notch or cutaway portion 35 is caused to embrace said yoke-piece by the upward tilting of the outer end of said carrier-arm. When it is desired to release the carrier-arm from such locked position its outer end is 20 merely pushed downward to disengage said notch or cutaway portion from its embracing position, whereupon the carrier-arm may be drawn backward or outward. The inner end of said carrier-arm is properly formed 25 to conform to the wrench-frame 36, so that the latter may be dropped upon said inner end of the carrier-arm and there held against any longitudinal movement upon said carrier-arm. When said parallel lever- 30 members 26 and 26' are swung inwardly it will be apparent that the inner end of said carrier-arm, upon which is mounted the wrench-frame 36, will be moved inward and will thereupon carry the latter between and 35 in contact with the respective abrading belts 22. This inward swinging movement of said parallel lever-members 26 and 26' is accomplished by means of the following system of counterbalanced operating levers, 40 comprising a fulcrum link 37, the inner end of which is pivotally connected with a stud 38 which projects from the inner side of one of said standards 3. The said fulcrum link extends outwardly between said pairs of 45 parallel lever-members 26 and 26', and pivotally connected with the same, so as to be fulcrumed upon its free end is a hand-lever 39, from which extends outwardly an arm 40. Pivotally connected with the free end 50 of said arm 40 is a link-member 41, which extends inwardly, so that its inner end is pivotally connected with one end of a counter-balance lever 42, the latter being fulcrumed upon said stud 38, and having ad- 55 justably fixed upon its opposite end a counter-balance weight 43. Connected with and extending transversely between said lever-members 26' of said parallel lever-members is a cross-bar 44 having perforations 45 therein. Said link-member 41 is provided with a downwardly extending coupling-pin 46 which enters one of the perforations 45 of said cross-bar 44, thereby connecting said link-member with said cross-bar and conse- 60 quently with said parallel lever-members. 65

When said hand-lever 39 is pulled downwardly it swings upon its pivotal connection with said fulcrum link 37 thereby swinging inwardly the arm 40, which in turn pushes inwardly said link-member 41, the inward 70 movement of which is transmitted through said coupling-pin 46 and cross-bar 44 to said parallel lever-members 26 and 26', which are consequently caused to swing inwardly to carry the carrier-table and work holding 75 device connected therewith inwardly toward said abrading belts 22. The weight of said parallel lever-members and the parts connected therewith is counter-balanced by the counter-balance lever 42 and the weight 43 80 connected therewith, and which is synchronously operated in proper directions by the movement of said link-member 41 with which they are connected.

Secured to the inner side surface of each 85 standard 3 is a guide-member 47 in which is slidably disposed a carrier-bar 48. Secured to the free end of each carrier-bar 48 is a bracket-member 49 to which are pivotally connected pairs of parallel suspending 90 levers 50 and 50'. Pivotally secured between the lower free ends of said parallel suspending levers 50 and 50' are carrier-plates 51. The said carrier-bars 48 and said carrier-plates 51 thus suspended therefrom, are so 95 disposed as to be presented in a plane behind the inner stretches of the superimposed portions of said backing belts 21 and abrading belts 22. Mounted upon each carrier-plate 51, and conveniently affixed thereto, are de- 100 vices adapted to be moved into contact with said superimposed stretches of said backing and abrading belts simultaneously with the introduction of the work to be ground therebetween, so as to press said abrading belts in 105 proper grinding contact with the surface of said work. These devices comprise a suitable frame-work 52, in which are slidably disposed a plurality of pressing-fingers 53, the free ends 54 of which project from said 110 frame-work 52 toward the respective superimposed stretches of said backing and abrading belts. The said pressing-fingers 53 are preferably so disposed and arranged in their supporting frame-work 52 that the combined 115 area of their pressing or contacting ends conform substantially both to the outline and area of the surface of the casting or other work against which they are designed to press the abrading-belt 22, as backed by 120 the backing-belt 21. Each pressing-finger 53 is provided at its inner end with a tail-piece 55 of substantially reduced cross-sec- 125 tional area with relation to the cross-sec- tional area of the main body of the said pressing-finger. Secured within said frame-work 52 is a resilient element, preferably in the form of a block of soft rubber 56, against which the ends of said tail-pieces 55 con- 130 tact to resiliently or yieldingly back said

pressing-fingers 53. Each pressing-finger 53 is further provided with a suitably disposed cutaway-portion 57 which embraces a companion stop-member 58 for each pressing-finger, which stop-members are suitably affixed in stationary relation to said framework 52, and since said cutaway-portions 57 are longer than the width of said stop-members a limited longitudinal movement 10 of said pressing-fingers 53 is permitted without permitting the same to be disconnected from their properly associated relation with said frame-work 52.

Affixed to the outer ends of each carrier-plate 51 is a cam-plate 59 the outer edge of 15 which forms an outwardly curved cam-portion 60.

The reference character 61 indicates adjustable yoke-members which are adjustably 20 related to the said parallel lever-members 26 and 26'. Connected with, and extending between said yoke-pieces 61 is a cross-bar 62. Each carrier-bar 48 is provided with a stud 63, and interconnecting each stud 63 with 25 said cross-bar 62 are connecting links 64, the same having a plurality of notches 65 adjacent to each end thereof, which may be selectively engaged respectively with said studs 63 and said cross-bar 62 to properly 30 position said pressing devices carried by said carrier-bars 48 relatively to said work carrying devices carried by said parallel lever-members 26 and 26', so that a simultaneous inward movement toward said abrading elements of all said parts may be caused by the 35 inward swinging movement of said parallel lever-members 26 and 26'. The normal positions of said carrier-plates 51, as supported by said suspending levers 50 and 50', and 40 consequently of said pressing devices carried by said carrier-plates 51, are such that the free ends 54 of the pressing-fingers 53 are normally removed from the plane of said superimposed stretches of said backing and 45 abrading belts, these positions being determined by stop-members 66 which are secured to each bracket-member 49, and against which the suspending-levers 50 50' are brought to rest when said carrier-plates 51 and the pressing devices mounted thereon, 50 are free, under the force of gravity, to swing away from said belts.

The reference character 67 indicates base-plates which are respectively secured to the 55 forward faces of said standards 3 in suitable locations. Secured to each base-plate is an outwardly extending bracket 68. Fulcrumed in the free end of each bracket 68 is a pressure lever 69. Each bracket 68 is provided on one side with a downwardly extending wall or flange 70, having a suitably disposed opening or perforation 71 therein. The tail 72 of said pressure lever 69 is stopped against said wall or flange 70, thus 60 fixing its normal position. Pivottally con-

nected with said tail 72 of said pressure-lever 69 is a rod 73 which extends through the opening or perforation 71 of said wall or flange 70 and which is thus caused to extend outwardly therefrom. The free end of said rod 73 is screw threaded so as to receive thereon lock-nuts 74. Arranged upon said rod between said lock-nuts 74 and said wall or flange 70 is a pressure spring 75. With 70 said wall or flange 70 as a base and said lock-nuts as a point of purchase said pressure spring 75 exerts an outwardly moving pressure upon said rod 73 and consequently 75 upon said pressure-lever 69, thereby normally maintaining the latter in its stopped position with its tail 72 against the inner side of said wall or flange 70, and its outer free end projected into the path of said cam-plate 59 connected with each of said carrier-plates 51. Said outer free end of 80 said pressure-lever 69 is provided with an anti-friction roller 76. When said carrier-plates 51 are carried inward by the inwardly swinging movement of said parallel lever-members 26 and 26', as above described, the 85 cam-plates 59 are moved into contact with the anti-friction rollers 76 of said pressure-levers 69, and as this inward movement is continued the cam-portions 60 ride upon said anti-friction rollers 76. The result of 90 this movement is to cause a forward swinging movement of said carrier-plates 51, as suspended by said suspending levers 50 and 50', toward the superimposed stretches of 95 said backing and abrading belts, so that by 100 the time the work enters between the opposed operative surfaces of the abrading belts the said pressing devices carried by said carrier plates 51 are moved inwardly 105 whereby the free ends 54 of the pressing-fingers are brought into contact with the back of the superimposed stretches of said backing and abrading belts. It will be apparent that when the pressing devices are thus brought into contact with the said 110 backing and abrading belts, the same are held yieldingly in contact with the said belts by reason of the tension or pressure of said pressure-springs 75, as transmitted to said carrier-plates 51 and the pressing devices 115 supported thereon by the pressure-levers 69; this yieldable condition being in addition to the resilient backing of the individual pressing-fingers 53, as already above described. Owing to the interconnected relation of said 120 carrier-bars 48 with said parallel lever-members 26 and 26', the pressing devices suspended from said carrier-bars 48 will move inwardly simultaneously with the inward movement of the work to be operated 125 upon as carried by said carrier-table 28 and the work-supporting devices mounted thereon, but since the means interconnecting said carrier-bars 48 with said parallel lever-members 26 and 26', viz. the yoke members 61 130

and the cross-bar 62 connected therewith, are secured to said parallel lever-members 26 and 26' at points between the extremities of said lever-members and their fulcrums, it follows that the radius of the arc of movement of said yoke-members 61 and cross-bar 62 is shorter than the radius of the arc of movement of said carrier-table 28, consequently upon the inward swinging movement of said parallel lever-members 26 and 26', the distance of travel of said pressing devices relative to the distance of travel of said work to be operated upon will be less than the latter. The work as it passes between the abrading elements is also given a slight vertical movement relative to the pressing devices, and this is by reason of the fact that the table 28 swinging on said parallel lever members 26 and 26' describes a descending arc, which not only causes the work to be carried laterally across the abrading surface of the abrading elements but also vertically moves the work as well. This vertical movement of the work is relative to the pressing members since the latter, being supported by said carrier-bars 48 do not move vertically but only laterally across the abrading elements. The ratio of the respective lateral movements of said pressing devices and the work to be operated upon as thus accomplished is subject to adjustment by reason of means for securing said yoke-members 61 in various positions in connection with said lever-members 26 and 26', whereby said yoke-members 61 and cross-bar 62 may be positioned nearer to or farther away from the fulcrums of said lever-members. This means of adjustment comprises the provision in said parallel lever-members of a plurality of longitudinally disposed perforations or openings 77, and in the provision of longitudinally disposed perforation or openings 78 in the vertical portions of said yoke-members 61. Any selected opening or perforation 78 may be registered with any of said openings or perforations 77 whereby the desired distance of said yoke-members 61 and cross-bar 62 from the fulcrums of said lever-members, relative to the distance of the work as supported by said carrier-table 28 on work supporting devices suspended by said lever-members, may be secured. When the yoke-members 61 are thus positioned fastening screws or pins 79 may be inserted through the said registered openings or perforations. As previously mentioned the said standards 3 are movable laterally away from or toward each other for the purpose of properly spacing the superimposed stretches of said backing and abrading belts from each other so that the latter will be properly spaced to accommodate the width of the work to be inserted therebetween. It follows that any adjustment of said standards 3 will require

a readjustment of said parallel lever members 26 and 26' to position the same so that the carrier-table 28 will be properly disposed to support the work carrying devices in line with the readjusted positions of 70 said backing and abrading belts. To this end the supporting shafts 25 and 25' are movable longitudinally in the bearing blocks 24, so that the said shafts and lever-members may be moved laterally to a proper 75 adjusted position. When thus properly positioned the said shafts 25 and 25' are retained against further longitudinal movement by means of a pair of stop-collars 80 which are positioned on opposite sides of 80 certain of said bearing-blocks 24, and then locked upon said shafts.

Having thus described the general construction of the various devices and detailed parts comprising the novel grinding and 85 polishing machine embodying the principles of my invention, it remains to describe the operations, uses, and advantages of the same. The said novel grinding and polishing machine is adapted to be used to finish 90 the surfaces of rough castings, and the like. The surfaces of such castings are usually rough and contain in their surface area inequalities comprising high and low spots, which are due to unequal shrinkage of the 95 metal when cooling, and to warping and similar causes. It is desirable to so grind such surfaces as to not only smooth off the roughness of the surface but to eliminate the appearance of these inequalities, so that 100 said surfaces appear even, level and smooth even while the inequalities comprising the high and low spots remain. But this finished appearance must be accomplished without grinding down said high spots to 101 the plane of said low spots of the surface of said casting, since such method would tend to weaken the casting. To accomplish the desired result I provide the novel pressing devices whereby the abrading belt is pressed 110 with substantial uniformity upon all points of the area of the surface to be ground, and at the same time by moving the work, while in contact with the abrading belts relatively to the ends of the pressing fingers 53, so 115 that the latter do not press the abrading-belts against only a given portion of the surface of the work, but rather ride in and out of the inequalities of the surface. Such action of the fingers 53 is obtained by providing the different ratios of traveling movement of the work and pressing-devices as accomplished by the inward movement of 120 said parallel lever-members 26 and 26' in the manner above described.

As illustrative of the character of the work adapted to be operated upon by my machine, I have selected as an example a wrench-frame 36, such as forms a part of the usual construction of Stillson-wrenches. 125

The said wrench-frame 36 is mounted upon the end of the carrier-arm 33, which is then thrust to its inwardly moved position. The hand-lever 39 is then pulled downwardly 5 to swing inwardly the parallel lever members 26 and 26', which causes the inward movement of said carrier-table 28 and said carrier-arm 33, thereby inserting said wrench-frame 36 between the opposed faces 10 of said abrading-belts 22. As the wrench-frame 36 passes between the abrading-belts 22, the pressing devices are also moved inwardly, and operating in the manner above described are simultaneously forced toward 15 said superimposed stretches of said backing and abrading belts. The pressing-fingers 53 thereupon engage the backing-belts 21 and press the same, and the abrading belts 22 imposed thereon, against the side surfaces 20 of the wrench-frame 36. A continued movement of said lever-members 26 and 26' will then move the wrench-frame across the abrading surfaces of the belts 22, and this movement is followed by a corresponding 25 movement of the pressing-fingers 53. But since the arc of travel of said pressing-fingers 53 is less than the arc of travel of said work or wrench-frame 36 (as already above described), the latter travels faster across 30 the belts than the former, consequently its surfaces are constantly shifting in advance of or across the abrading belt as pressed forward by said pressing-fingers 53, so that the latter, in effect, cause said abrading 35 belts to ride in and out of the hollows or low spots of the casting or surface of the wrench-frame 36, and consequently the moving abrading belt contacts with substantial uniformity with all portions of the 40 surface area of said wrench frame, rendering the lines of abrasion on said surface continuous, even and uniform, so that to all appearance the surface of the casting or wrench frame 36 is seemingly level 45 and even. A reverse movement of the lever-members 26 and 26' withdraws said wrench frame 36 from contact with the abrading belts 22, and the same may be removed from the carrier-arm 33, and another wrench-frame replaced thereon for 50 a repetition of the above described operations.

Referring now to Fig. 7 of the drawings, I have illustrated therein a slightly modified 55 arrangement and mounting of the pressing means for holding the abrading elements in contact with the work. In this construction instead of suspending the pressing devices from carrier bars 48 slidably mounted in 60 connection with the standards 3, I provide a pair of bracket-members 81, which are secured upon the table 28, one on either side of the work holding means. These bracket-members 81 extend inwardly parallel to the work-holding means, and their free ends

are provided with laterally disposed housing-portions 82 in which are slidably disposed the tail-portions 83 of pressing-members 84. Secured to the ends of said tail-portions 83 are the cam-plates 59 provided 70 with the cam-portions 60. The said pressing-members 84 are normally registered opposite the work 85 carried by the carrier-arm 33 of the work-holding means. When the said table 28, as supported by said parallel lever-members 26 and 26', is moved inwardly toward said abrading elements the work 85 is carried between said abrading elements 22, and the pressing-members 84 are carried in back of said abrading elements. 75 Simultaneously said cams 60 of said cam-plates 59 contacting with the rollers 76 of the spring actuated pressure-levers 69, the pressing members are caused to move in contact with the abrading elements forcing the same 80 in contact with the work 85, this contact being yieldable by reason of the spring contact of said pressure-levers 69. Since the pressing-members 84 are mounted in connection with said table 28 it will be apparent that 85 the same are caused to move simultaneously with the work and laterally across the abrading elements uniformly with the work. For certain classes of work this arrangement and operation is more desirable than the arrangement and operation of the heretofore described mounting of the pressing members, the general principles of operation being retained however in this modified construction. 90

As many changes may be made in the above described construction of my invention and its detail parts, and many apparently widely different embodiments of my invention could be made without departing 105 from the scope thereof, I intend that all matter contained in the above description or shown in the accompanying drawings shall be interpreted as illustrative and not in a limiting sense. I desire it also understood that the language used in the following claims is intended to cover all generic and specific features of the invention herein described, and all statements of the scope of the invention, which, as a matter of language, might be said to fall therebetween. Hence, I do not limit my present invention to the exact arrangements and combinations of the devices and parts as described in the said specification, nor do I confine myself 110 to the exact details of the construction of the said parts, as illustrated in the accompanying drawings. 115

I claim:

1. In a device of the class described, an 125 abrading means, means for feeding the work to be ground in contact therewith, means for pressing said abrading means to the work, and means for causing said pressing means to travel with the work while the 130

latter moves in contact with said abrading means.

2. In a device of the class described, an abrading means, means for feeding the work to be ground in contact therewith, means for pressing said abrading means to the work, said pressing means having a pressing surface of substantially the same conformation and outline as the surface of the work to be ground, and means for producing simultaneous accompanying lateral movements of said pressing means and said work while respectively in contact with opposite sides of said abrading means.

15 3. In a device of the class described, an abrading means, means for pressing said abrading means to the work, and means for producing variable relative lateral movements of said pressing means and said work while respectively in contact with opposite sides of the abrading means.

4. In a device of the class described, an abrading means, means for feeding the work to be ground in contact therewith, means for pressing said abrading means yieldingly to the work, means for synchronously moving said pressing means into operative contact with said abrading means upon the introduction of the work to the latter, and means for producing variable relative lateral movements of said pressing means and said work while respectively in contact with opposite sides of said abrading means.

35 5. In a device of the kind described, abrading means adapted to engage opposite sides of a piece of work, a carrier table provided with work holding means, parallel lever members upon the free ends of which said carrier-table is suspended, means for swinging said parallel lever members toward and away from said abrading means to feed the work laterally across and in contact with said abrading means, movable means for pressing said abrading means to the work, means for holding said pressing means yieldingly against the backs of said abrading means, and means for adjustably connecting said pressing means with said parallel lever members whereby a greater or less proportional lateral movement of said pressing means relative to the lateral movement of said work is produced.

55 6. In a device of the class described, abrading means adapted to engage opposite sides of a piece of work, means for pressing said abrading means to the work, a work holding means, and means for controlling the movements of said pressing means and said work holding means whereby the work and said pressing means are caused to travel laterally across the abrading means while respectively in contact with opposite sides of said abrading means.

65 7. In a device of the class described, abrading means adapted to engage opposite

sides of a piece of work, means for pressing said abrading means to the work, means for forcing said pressing means yieldingly in engagement with said abrading means, a work holding means, and means for synchronously controlling the movements of said pressing means and said work holding means whereby the work and said pressing means are caused to travel laterally across the abrading means while respectively in contact with opposite sides of said abrading means.

8. In a device of the class described, a pair of oppositely facing abrading belts, means for supporting and driving the same, a work holding means, means for moving said work holding means to carry the work to and move the same laterally between said abrading belts, and means movable toward the backs of said abrading belts for pressing said abrading belts against said work while the latter moves in contact with the former.

9. In a device of the class described, a pair of oppositely facing abrading belts, means for supporting and driving the same, means for feeding the work to be ground between and laterally across the faces of the same, means for pressing said abrading belts to the work, and means interconnecting said pressing means with said work feeding means whereby said pressing means are moved laterally across the rear sides of said abrading belts synchronously with the movement of said work laterally between and in contact with said abrading belts.

10. In a device of the class described, a pair of oppositely facing abrading belts, means for supporting and driving the same, means for feeding the work to be ground between and laterally across the faces of the same, means for pressing said abrading belts to the work, means interconnecting said pressing means with said work feeding means whereby said pressing means are moved laterally across the rear sides of said abrading belts synchronously with the movement of said work laterally between and in contact with said abrading belts, and means for adjusting the interconnected relation of said pressing means with said work feeding means whereby the ratio of the lateral movement of said pressing means may be varied with relation to the lateral movement of said work.

11. In a device of the class described, a pair of oppositely facing abrading belts, means for supporting and driving the same, means for feeding the work to be ground between and laterally across the faces of the same, means for pressing said abrading belts to the work comprising, a frame-work, longitudinally and independently movable pressing-fingers mounted in said frame-work and disposed at right angles to the

plane of said abrading belts, and a resilient means engaging the rear ends of said pressing-fingers, a carrying means for supporting said frame-work and its pressing-fingers, means engageable by said carrying means for moving the latter toward the backs of said abrading belts and holding the same yieldingly with relation to said abrading belts, and means interconnecting said carrying means with said work feeding means whereby said pressing-fingers carried thereby are moved laterally across the backs of said abrading belts synchronously with the movement of said work laterally between and in contact with said abrading belts.

12. In a device of the class described, a pair of oppositely facing abrading belts, means for supporting and driving the same, means for feeding the work to be ground between and laterally across the faces of the same, means for pressing said abrading belts to the work comprising, a frame-work, longitudinally and independently movable pressing-fingers mounted in said frame-work and disposed at right angles to the plane of said abrading belts, and a resilient means engaging the rear ends of said pressing-fingers, a carrying means for supporting said frame-work and its pressing-fingers, means engageable by said carrying means for moving the latter toward the backs of said abrading belts and holding the same yieldingly with relation to said abrading belts, means interconnecting said carrying means with said work feeding means whereby said pressing-fingers carried thereby are moved laterally across the backs of said abrading belts synchronously with the movement of said work laterally between and in contact with said abrading belts, and means for adjusting the interconnected relation of said carrying means with said work feeding means whereby the ratio of the lateral movement of said pressing-fingers may be varied with relation to the lateral movement of said work.

13. In a device of the class described, a base, a pair of standards movable upon said base, each standard having means for mounting an abrading belt, said abrading belts being mounted with their inner stretches facing each other, means for driving said abrading belts, a carrier-table provided with work holding means, means for suspending said carrier-table so that the same may be swung toward said abrading belts to feed the work to be ground between and laterally across the faces of the same, means for pressing said abrading belts to the work, means for forcing said pressing means yieldingly in engagement with said abrading belts, and means for synchronously controlling the movements of said pressing means and said carrier table whereby the work and said

pressing means are caused to travel laterally across the abrading belts while respectively in contact with opposite sides of said abrading belts.

14. In a device of the class described, a pair of oppositely facing abrading belts, means for supporting and driving the same, a carrier-table provided with work-holding means, and parallel lever members for suspending said carrier-table so that the same may be swung toward said abrading belts to feed the work to be ground between and laterally across the faces of said abrading belts.

15. In a device of the class described, a pair of oppositely facing abrading belts, means for supporting and driving the same, a carrier-table provided with work-holding means, parallel lever members for suspending said carrier-table so that the same may be swung toward said abrading belts to feed the work to be ground between and laterally across the faces of said abrading belts, means for pressing said abrading belts to the work, and means interconnecting said pressing means with said parallel lever members whereby said pressing means are moved laterally across the rear sides of said abrading belts synchronously with the movement of said work laterally between and in contact with said abrading belts.

16. In a device of the class described, a pair of oppositely facing abrading belts, means for supporting and driving the same, a carrier-table provided with work-holding means, parallel lever members for suspending said carrier-table so that the same may be swung toward said abrading belts to feed the work to be ground between and laterally across the faces of said abrading belts, means for pressing said abrading belts to the work, means interconnecting said pressing means with said parallel lever members whereby said pressing means are moved laterally across the rear sides of said abrading belts synchronously with the movement of said work laterally between and in contact with said abrading belts, and means for adjusting the interconnected relation of said pressing means with said parallel lever-members whereby the ratio of the lateral movement of said pressing means may be varied with relation to the lateral movement of said work.

17. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket members projecting from said standards, a lateral shaft journaled in said bracket members, parallel lever members depending from said shaft for suspending said carrier-table

so that the same may be swung toward said abrading belts to feed the work to be ground between and laterally across the faces of said abrading belts, and means for controlling the movements of said parallel lever members.

18. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket-members projecting from said standards, a lateral shaft journaled in said bracket members, parallel lever members depending from said shaft for suspending said carrier-table so that the same may be swung toward said abrading belts to feed the work to be ground between and laterally across the faces of said abrading belts, means for controlling the movements of said parallel lever members, means for pressing said abrading belts to the work, and means interconnecting said pressing means with said parallel lever members whereby said pressing means are moved laterally across the rear sides of said abrading belts synchronously with the movement of said work laterally between and in contact with said abrading belts.

19. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket members projecting from said standards, a lateral shaft journaled in said bracket members, parallel lever members depending from said shaft for suspending said carrier-table so that the same may be swung toward said abrading belts to feed the work to be ground between and laterally across the faces of said abrading belts, means for controlling the movements of said parallel lever members, means for pressing said abrading belts to the work, means interconnecting said pressing means with said parallel lever members whereby said pressing means are moved laterally across the rear sides of said abrading belts synchronously with the movement of said work laterally between and in contact with said abrading belts, and means for adjusting the interconnected relation of said pressing means with said parallel lever members whereby the ratio of the lateral movement of said pressing means may be varied with relation to the lateral movement of said work.

20. In a device of the class described, a pair of oppositely facing abrading belts, standards provided with means for support-

ing and driving said abrading belts, a base upon which said standards are movably supported so as to be adjustable toward or away from each other, a carrier-table provided with work-holding means, bracket-members 70 projecting from said standards, a lateral shaft journaled in said bracket members, parallel lever members depending from said shaft, for suspending said carrier-table so that the same may be swung toward said 75 abrading belts to feed the work to be ground between and laterally across the faces of said abrading belts, means for controlling the movements of said parallel lever members, carrier-bars slidably mounted to project from the faces of said standards, carrier plates suspended from said carrier-bars adapted to swing toward the backs of the opposed stretches of said abrading belts, a frame-work mounted on each carrier-plate, 80 longitudinally and independently movable pressing fingers mounted in said frame-work and disposed at right angles to the plane of said abrading belts, resilient means 85 engaging the rear ends of said pressing fingers, means engageable by said carrier-plates for moving the same toward the backs of said abrading belts and holding the same yieldingly with relation to said abrading belts, and connecting links between said carrier-bars and said parallel lever members 90 whereby said pressing-fingers are moved laterally across the backs of said abrading belts synchronously with the movement of said work laterally between and in contact 95 with said abrading belts.

21. In a device of the class described, a pair of oppositely facing abrading belts, standards provided with means for supporting and driving said abrading belts, a base 100 upon which said standards are movably supported so as to be adjustable toward or away from each other, a carrier-table provided with work-holding means, bracket-members projecting from said standards, a lateral 105 shaft journaled in said bracket members parallel lever members depending from said shaft for suspending said carrier-table so that the same may be swung toward said abrading belts to feed the work to be ground between and laterally across the faces of said abrading belts, means for controlling the movements of said parallel lever members, carrier-bars slidably mounted to project from the faces of said standards, car- 110 rier plates suspended from said carrier-bars adapted to swing toward the backs of the opposed stretches of said abrading belts, a frame-work mounted on each carrier-plate, longitudinally and independently movable 115 pressing fingers mounted in said frame-work and disposed at right angles to the plane of said abrading belts, resilient means engaging the rear ends of said pressing fin- 120 gers, means engageable by said carrier-plates 125 whereby said pressing-fingers are moved laterally across the backs of said abrading belts synchronously with the movement of said work laterally between and in contact with said abrading belts.

130

for moving the same toward the backs of said abrading belts and holding the same yieldingly with relation to said abrading belts, connecting links between said carrier-bars and said parallel lever members whereby said pressing fingers are moved laterally across the backs of said abrading belts synchronously with the movement of said work laterally between and in contact with 10 said abrading belts, and means for adjusting the connected relation of said connecting links with said parallel lever members whereby the ratio of the lateral movement of said pressing fingers may be varied with 15 relation to the lateral movement of said work.

22. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket-members 20 projecting from said standards, a lateral shaft journaled in said bracket-members, parallel lever members depending from said shaft for suspending said carrier-table so that the same may be swung toward said 25 abrading belts to feed the work to be ground between and laterally across the faces of said abrading belts, means for controlling the movements of said parallel lever members, carrier-bars slidably mounted to project 30 from the faces of said standards, carrier-plates suspended from said carrier-bars adapted to swing toward the backs of the opposed stretches of said abrading belts, a frame-work mounted on each carrier-plate, 35 longitudinally and independently movable pressing fingers mounted in said frame-work and disposed at right angles to the plane of said abrading belts, resilient means engaging the rear-ends of said pressing fingers, a cam-plate at the outer end of each carrier-plate, a spring retained lever arm against 40 which said cam-plate moves to swing said carrier-plates toward the backs of said abrading belts and whereby the carrier-plates are held yieldingly with relation to said abrading-belts, and connecting links between said carrier-bars and said parallel lever members whereby said pressing fingers are moved laterally across the backs of said 45 abrading belts synchronously with the movement of said work laterally between and in contact with said abrading belts.

45 means engageable by said carrier-plates for moving the same toward the backs of said abrading belts and holding the same yieldingly with relation to said abrading belts, connecting links between said carrier-bars 50 and said parallel lever members whereby said pressing-fingers are moved laterally across the backs of said abrading belts synchronously with the movement of said work laterally between and in contact with said 55 abrading belts, and means for adjusting the connected relation of said connecting links with said parallel lever-members whereby the ratio of the lateral movement of said pressing fingers may be varied with relation 60 to the lateral movement of said work, comprising yoke-members connected with said parallel lever members, means for adjustably securing said yoke-members nearer to or farther away from the fulcrum of said 65 parallel lever members, and means connected

with said yoke-members to which said connecting links are secured.

23. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket members 70 projecting from said standards, a lateral shaft journaled in said bracket-members, parallel lever members depending from said shaft for suspending said carrier-table so that the same may be swung toward said 75 abrading belts to feed the work to be ground between and laterally across the faces of said abrading belts, means for controlling the movements of said parallel lever members, carrier-bars slidably mounted to project 80 from the faces of said standards, carrier-plates suspended from said carrier-bars adapted to swing toward the backs of the opposed stretches of said abrading belts, a frame-work mounted on each carrier-plate, 85 longitudinally and independently movable pressing fingers mounted in said frame-work and disposed at right angles to the plane of said abrading belts, resilient means engaging the rear-ends of said pressing fingers, a 90 cam-plate at the outer end of each carrier-plate, a spring retained lever arm against which said cam-plate moves to swing said carrier-plates toward the backs of said 95 abrading belts and whereby the carrier-plates are held yieldingly with relation to said abrading-belts, and connecting links between said carrier-bars and said parallel lever members whereby said pressing fingers are moved laterally across the backs of said 100 abrading belts synchronously with the movement of said work laterally between and in contact with said abrading belts.

24. In a device of the class described, a pair of oppositely facing abrading belts, standards provided with means for supporting and driving said abrading belts, a base upon which said standards are movably supported so as to be adjustable toward or away from each other, a carrier-table provided 110 with work-holding means, bracket-members projecting from said standards, a lateral shaft journaled in said bracket members, parallel lever members depending from said shaft for suspending said carrier-table so 115 that the same may be swung toward said abrading belts to feed the work to be ground between and laterally across the faces of said abrading belts, means for controlling the movements of said parallel lever members, carrier-bars slidably mounted to project 120 from the faces of said standards, carrier-plates suspended from said carrier-bars adapted to swing toward the backs of the opposed stretches of said abrading belts, a 125 130

- frame-work mounted on each carrier-plate, longitudinally and independently movable pressing fingers mounted in said frame-work and disposed at right angles to the plane of said abrading belts, resilient means engaging the rear-ends of said pressing fingers, a cam-plate at the outer end of each carrier-plate, a spring retained lever arm against which said cam-plate moves to swing said carrier-plates toward the backs of said abrading belts and whereby the carrier-plates are held yieldingly with relation to said abrading-belts, connecting links between said carrier-bars and said parallel lever members whereby said pressing fingers are moved laterally across the backs of said abrading belts synchronously with the movement of said work laterally between and in contact with said abrading belts, and means for adjusting the connected relation of said connecting links with said parallel lever-members whereby the ratio of the lateral movement of said pressing fingers may be varied with relation to the lateral movement of said work.
25. In a device of the class described, a pair of oppositely facing abrading belts, standards provided with means for supporting and driving said abrading belts, a base upon which said standards are movably supported so as to be adjustable toward or away from each other, a carrier-table provided with work-holding means, bracket members projecting from said standards, a lateral shaft journaled in said bracket members, parallel lever members depending from said shaft for suspending said carrier-table so that the same may be swung toward said abrading belts to feed the work to be ground between and laterally across the faces of said abrading belts, means for controlling the movements of said parallel lever members, carrier-bars slidably mounted to project from the faces of said standards, carrier-plates suspended from said carrier-bars adapted to swing toward the backs of the opposed stretches of said abrading belts, a frame-work mounted on each carrier-plate, longitudinally and independently movable pressing fingers mounted in said frame-work and disposed at right angles to the plane of said abrading belts, resilient means engaging the rear-ends of said pressing fingers, a cam-plate at the outer end of each carrier-plate, a spring retained lever arm against which said cam-plate moves to swing said carrier-plates toward the backs of said abrading belts and whereby the carrier-plates are held yieldingly with relation to said abrading-belts, connecting links between said carrier-bars and said parallel lever members whereby said pressing fingers are moved laterally across the backs of said abrading belts synchronously with the movement of said work laterally between and in contact with said abrading belts, and means for adjusting the connected relation of said connecting links with said parallel lever-members whereby the ratio of the lateral movement of said pressing fingers may be varied with relation to the lateral movement of said work.
30. In a device of the class described, an abrading means, and means for pressing said abrading means to the work to be ground, comprising a supporting frame-work, a plurality of longitudinally and independently movable pressing fingers the outer extremities of which are directed toward said abrading means, each pressing-finger having a tail portion of reduced cross sectional area, and a fixed body of resilient material with which said tail-portions contact.
35. In a device of the class described, an abrading means, and means for pressing said abrading means to the work to be ground, comprising a supporting frame-work, a plurality of longitudinally and independently movable pressing fingers the outer extremities of which are directed toward said abrading means, each pressing-finger having a tail portion of reduced cross sectional area, and a fixed body of resilient material with which said tail-portions contact.
40. In a device of the class described, an abrading means, and means for pressing said abrading means to the work to be ground, comprising a supporting frame-work, a plurality of longitudinally and independently movable pressing fingers the outer extremities of which are directed toward said abrading means, each pressing-finger having a tail portion of reduced cross sectional area, and a fixed body of resilient material with which said tail-portions contact.
45. In a device of the class described, an abrading means, and means for pressing said abrading means to the work to be ground, comprising a supporting frame-work, a plurality of longitudinally and independently movable pressing fingers the outer extremities of which are directed toward said abrading means, each pressing-finger having a tail portion of reduced cross sectional area, and a fixed body of resilient material with which said tail-portions contact.

In testimony, that I claim the invention set forth above I have hereunto set my hand this 24th day of March, 1914.

JOHN C. BLEVNEY.
